EDUCATIONAL BOARD FOR TEACHING CHILDREN WITH DISABILITIES

Johanna R. Rotkow, 735 55th St.,
Des Moines, Iowa 50312

Filed Oct. 23, 1970, Ser. No. 55,627

Term of patent 14 years

Int. Cl. D19—08

U.S. Cl. D25—1

FIG. 1 is a top perspective view of an educational board for teaching children with disabilities showing my new design and looking toward the front side thereof;

FIG. 2 is a top perspective looking toward the rear side of the educational board;

FIG. 3 is a side elevational view; and

FIG. 4 is a front elevational view.

I claim:

The ornamental design for an educational board for teaching children with disabilities, substantially as shown.
